[57] **CLAIM**

The ornamental design for a fire-place, as shown and described.

DESCRIPTION

FIG. 1 is a front elevational view of a fire-place showing my new design;

FIG. 2 is a side elevational view thereof, the side opposite that shown in FIG. 2 being the mirror image thereof;

FIG. 3 is a top plan view thereof;

FIG. 4 is a rear elevational view thereof; and

FIG. 5 is a perspective view thereof from above.

*Fig. 1.**Fig. 2.**Fig. 3.*

Fig.4.
